UNITED STATES PATENT OFFICE.

JOEL W. McENTIRE, OF FORT WORTH, TEXAS, ASSIGNOR OF ONE-HALF TO JAMES A. WILLIAMS, OF FORT WORTH, TEXAS.

COLLAPSIBLE COOP.

Application filed September 13, 1923. Serial No. 662,532.

To all whom it may concern:

Be it known that I, JOEL W. McENTIRE, a citizen of the United States, residing at Fort Worth, in the county of Tarrant and State of Texas, have invented certain new and useful Improvements in Collapsible Coops, of which the following is a specification.

This invention relates to coops for poultry and the like, and refers more particularly to a collapsible coop that may be folded in a minimum of space when not in use, and may be quickly and readily extended from the minimum of space to its open position for use.

Features of the invention are the durability and simplicity of construction and the ease of which the coop may be set up for use, or collapsed for storage or for return shipment.

The primary object of the invention is to provide a coop that because of its simplicity and few working parts, may be manufactured for a small cost, and will withstand hard usage.

Other objects and features as well as the above will be set forth in the course of the following description of an embodiment of the invention, taken in connection with the drawings attached hereto in which;

Figure 1 represents a perspective view of the coop in an extended position.

Figure 2 is a top or plan view of the invention.

Figure 3 is a detail view, showing the method of folding the sides of the coop.

Figure 4 is a view of the invention in a collapsed position.

Figure 5 is a section of the framework of the coop showing the clasp arrangement.

Following the figures, in Figure 1, my preferred embodiment of the invention is shown, in which the top 1 and bottom 2 are set forth, same having a substantial wood and wire construction, the ends 3 fastened to the bottom by staples *b*—*b* and the sides 4 fastened to the bottom by staples *a*—*a*. The sides 4 are adapted to slide clearly upon the guide wires 8 as the top of the coop is raised away from the bottom, catches 9 supporting the guide wires 8 at their middle portion, and at the same time serving as a means for checking the outward movement of the ends 3 when they are in the raised

position, spring catch 7 shown in Figure 5 in detail, is so fastened at 7^a, to vertical member 4^a and horizontal member 4^b of the sides 4 as to be stationary and is also fastened at point 7^b around other vertical and horizontal members of the sides, thus forming a spring catch to hold ends 3 in the open position. The cover 5 for the top 1 shown in detail in the top view in Figure 2, is slidable over wires 6—6 below the members 7—7 of the cover.

In Figure 3, the structure and movement of the sides 4—4 over the guides 8—8 is shown, supporting and movement limiting means 9 being also shown.

In Figure 4, the coop is shown in collapsed position, with the top and cover structure removed to show the construction and arrangement of the sides and their guides.

In Figures 1 and 4, 10 represents the checking means for the outward movement of the sides, same being situated on the sides of the top centrally below the side edges.

It will be seen that the sides are raised first, and the ends after the sides, and the latter are raised against the side guides. It should be understood that the construction can be of any suitable material and may vary as to fastening and movement locking details, without departing from the spirit or intent of the invention, the idea being to do away with all but the necessary construction, the sides cannot be over one half in height to the width of the top, so that folding may be possible.

What is claimed is:

1. In a collapsible coop or the like, a bottom and a top of equal size, sides whose height is less than half the width of the top or the bottom, guides extending laterally beneath the top of the coop at each end, adapted to be slidably engaged by the upper edges of the sides, the lower edges of the sides being hinged to the bottom, ends hinged at their bottom sides to the bottom of the coop, and movable in an upward and outward direction, and means below the top to limit the movement of the sides and ends, and means on the sides to check and lock the ends, substantially as described.
2. In a collapsible coop, having a top and bottom of equal size, ends and sides pivot-

- ally attached at the bottom, the upper edges of the sides engageably guided by laterally extending means below the top at each end, and means below the top on each end and each side, to limit the movement of the sides and ends, an opening in the top, a cover slidably engaged below said opening, and means to fasten the cover in the sides and ends, substantially as described.
3. A collapsible coop, having sides and ends hinged to the bottom thereof, guides in the top to direct the extension movement of the sides and limit same, means in the top to lock the sides and ends thereto, means on the sides and ends to lock same together,
- 10 3. A collapsible coop, having sides and ends hinged to the bottom thereof, guides in the top to direct the extension movement of the sides and limit same, means in the top to lock the sides and ends thereto, means
- 15 on the sides and ends to lock same together,

and a cover slidably engaged over the opening in the top.

4. A collapsible coop having sides and ends pivoted to the side and end edges of the bottom; and guides and movement limiting means in the top for the said sides and ends; an opening in the top; a cover for said opening in slidably attachment thereto, and means on the sides or ends at their edges to lock same together in rigid relationship.

In testimony whereof I have signed my name to this specification.

JOEL W. McENTIRE.
